UNITED STATES PATENT OFFICE.

GEORGE A. COLGAN, OF NEW YORK, N. Y., ASSIGNOR TO GEORGE V. COOPER, OF BUFFALO, NEW YORK.

DESIGN FOR A PAPER-BOX BLANK.

SPECIFICATION forming part of Design No. 32,261, dated February 20, 1900.

Application filed January 12, 1900. Serial No. 1,247. Term of patent 14 years.

To all whom it may concern:

Be it known that I, GEORGE A. COLGAN, a citizen of the United States, and a resident of the city of New York, borough of Brooklyn, in the county of Kings and State of New York, have invented and produced a new and original Design for a Paper-Box Blank, of which the following is a full, clear, and exact specification.

- Reference is to be had to the accompanying drawing, forming a part of this specification, in which the figure is a face view of a paper-box blank, showing my design.

The design in its entirety consists of a bottom A, flanked by sides B and C, of which the side B appears at its ends with slotted flanges B', and the side C appears at its ends with tongue-flanges C', and from the inner edges of the flanges B' extend reinforce-flanges B'', along the outer edges of the bottom A and toward the flanges C', and the side C appears

flanked with a main top D, having its ends appearing with flanges D', terminating in flaps D'', and the top D is flanked by an auxiliary top E, appearing at its ends with flanges E', adjacent to the flanges D', and the several connected parts above enumerated appear with creases or scores F to readily distinguish the individual parts.

Having thus fully described my invention, I claim as new and desire to secure by Letters Patent—

The design for a paper-box blank, as herein shown and described.

In testimony whereof I have signed my name to this specification in the presence of two subscribing witnesses.

GEORGE A. COLGAN.
